UNITED STATES PATENT OFFICE.

WILLIAM J. AUMEN, OF ALLENTOWN, PENNSYLVANIA.

GRAIN-HARVESTER.

No. 875,682.

Specification of Letters Patent.

Patented Jan. 7, 1908.

Application filed November 8, 1907. Serial No. 401,266.

To all whom it may concern:

Be it known that I, WILLIAM J. AUMEN, citizen of the United States, residing at Allentown, in the county of Lehigh and State of Pennsylvania, have invented new and useful Improvements in Grain-Harvesters, of which the following is a specification.

My invention pertains to grain harvesters, and has for its object to provide a grain harvester embodying grain boards in combination with its platform and elevator; the said grain boards being under the control of the driver so that they may be quickly and easily raised and lowered as occasion demands during the progress of the machine, and both boards being arranged to prevent displacement of the grain when the machine is moving up a grade, and the board complementary to the elevator being constructed with a view of affording an unobstructed channel for the upward passage of the heads of both long and short grain and of adjusting said heads and preventing undue rearward movement of the same so as to assure proper supply of the grain, irrespective of its condition, to the table of the machine.

With the foregoing in mind the invention will be fully understood from the following description and claims when the same are read in connection with the drawings, accompanying and forming part of this specification, in which:

Figure 1 is a rear elevation of so much of a grain harvester as is necessary to illustrate the preferred embodiment of my invention the same being shown with both of the grain boards raised. Fig. 2 is an enlarged section taken in a plane through the platform of the machine and looking toward the elevator and showing both grain boards as lowered. Fig. 3 is an enlarged detail section taken in the plane indicated by the line 3—3 of Fig. 2 and showing the arrangement of the grain board of the elevator, relative to the lower and upper endless aprons of the elevator.

Similar letters designate corresponding parts in all of the views of the drawings, referring to which:

A is the platform of a grain harvester. B is the elevator frame of the harvester. C is the lower apron of the elevator; D, the upper apron of the elevator, and E, the conveyer or apron of the platform. These parts may be of the ordinary construction or of any other

construction compatible with the purposes 55 of my invention, and any suitable connections may be employed for driving the aprons or conveyers from one of the ground wheels of the machine. As shown in Figs. 2 and 3, the upper apron D of the elevator is preferably of a less width than the lower apron C thereof.

F is a grain board hinged to the rear edge of the platform A and arranged to swing vertically, and G is a grain board hinged to the 65 rear edge of the elevator frame B. The grain board G of the elevator is of right angle form in cross-section for an important purpose which will presently be pointed out, and the outer wall a of said board is preferably provided at its lower end with a flared extension b, the office of which is to assist the heads of the grain in entering the channel afforded by the angular grain board. When the said grain board G and the grain 75 board F are in their raised positions they may be depended on to prevent undue rearward movement of the grain when the machine is being moved up a hill, and it will also be evident that by virtue of its having 80 the outer wall a, the board G will serve the purpose stated when in its lower position. When the board G and the board F are in their raised positions, the machine is adapted for handling short grain, and it will be manifest that the angular board G will afford a 85 channel up which the heads of the grain may freely pass, and at the same time will adjust the heads so as to prevent choking and so as to assure the passage of the grain in 90 proper position to the table of the machine. When both of the boards F and G are lowered as shown in Fig. 2, the machine is adapted to handle long grain to advantage, and in this latter position it is clear that the 95 board G will afford a smooth and unobstructed channel up which the heads of the long grain may freely pass, and at the same time will prevent undue rearward movement of the heads and by adjusting the same—*i. e.*, 100 keeping the heads in the proper course, will assure the passage of grain in proper position to the table of the machine.

It frequently occurs that short grain and long grain will be found at different points 105 in a field, and it is therefore advantageous for the driver of the machine to be able to quickly raise and lower the grain boards F

and G without stopping the machine. For this reason I provide the mechanism best shown in Fig. 2 through the medium of which the driver may expeditiously and 5 easily raise and lower the boards F and G and adjustably fix the same. The said mechanism comprises a hand lever H, fulcrumed at c on the main frame of the machine and equipped with a spring-pressed 10 detent d, a segmental rack I fixed on the machine and arranged when engaged by the detent to adjustably fix the lever H and the parts connected therewith, a rock-shaft J, journaled in a bearing e on the frame and 15 having arms f and g the latter of which is provided with an angularly disposed portion h disposed and movable in a slotted bracket i on the back of the grain board F, a link K interposed between and connecting the arm 20 f of the rock-shaft J and the upper arm of the hand lever H, and a link L extending between and suitably connected to the outer wall a of the grain board G and the lower arm of the hand lever H. The upper arm 25 of the hand lever H is arranged within convenient reach of the driver on the seat M of the machine, and by virtue of the connections described in the foregoing it will be readily understood that when the detent d 30 is disengaged from the rack I, and the upper arm of the lever H is thrown toward the right in Fig. 2, the grain boards F and G will be raised to their closed positions, in which positions they may be adjustably 35 fixed by the driver permitting the detent d to reengage the rack I. Then when the upper arm of the lever H is at the right, and it is desired to lower the grain boards F and G, the same may be accomplished by the driver 40 disengaging the detent d from the rack I and throwing the upper arm of the lever H toward the left and then permitting the detent to reengage the rack. It will also be understood that through the medium of the 45 lever H, the connections described, and the coöperating segmental rack and detent, the grain boards F and G may be conveniently placed and adjustably fixed in positions intermediate their fully closed positions and 50 their fully open positions as the condition of the grain being harvested demands.

It will be gathered from the foregoing that while materially increasing the efficiency of a grain harvester, my improvements do not materially increase the cost of a harvester and do not add in an appreciable degree to the weight of the machine.

The construction herein illustrated and described constitute the best practical embodiment of my invention of which I am cognizant, but it is obvious that in the future practice of the invention such changes or modifications may be made as fairly fall within the scope of my invention as defined 60 in the claims appended.

Having described my invention, what I claim and desire to secure by Letters-Patent, is:

1. The combination with the elevator of a grain harvester, of a grain board, of angular form in cross-section, hinged to the rear edge 70 of the elevator frame, and means for detachably securing the said grain board in its raised position.
2. In a grain harvester, the combination 75 with an elevator comprising a frame, a lower apron, and an upper apron of a less width than the lower apron to afford an open space at the rear of the elevator, of a grain board, of angular form in cross-section, hinged to the 80 rear edge of the elevator frame, and means for detachably securing the said grain board in its raised position.
3. The combination with the elevator of a grain harvester, of a grain board, of right 85 angle form in cross-section, having a bottom wall hinged at its forward edge to the rear edge of the elevator frame and also having an outer wall, and means for detachably securing the said grain board in its raised position.
4. In a grain harvester, the combination 90 with an elevator comprising a frame, a lower apron, and an upper apron of a less width than the lower apron to afford an open space at the rear of the elevator, of a grain board having a bottom wall hinged at its forward edge 95 to the rear edge of the elevator frame and also having an outer wall disposed at a right angle to the bottom wall, and means for detachably securing the said grain board in its raised position.
5. The combination with the elevator of a grain harvester, of a grain board, of angular form in cross-section, hinged to the rear edge 100 of the elevator frame and having a flared extension at the lower end of its outer wall, and means for detachably securing the said grain board in its raised position.
6. The combination with the frame and 105 elevator of a grain harvester, of a grain board, of angular form in cross-section, hinged to the rear edge of the elevator frame, a lever mounted on the frame of the machine, a connection between said lever and the 110 grain board, and means for adjustably fixing the lever in the positions in which it is placed.
7. The combination with the frame, the platform and the elevator of a grain harvester, of a grain board hinged to the rear edge 115 of the platform, a grain board, of angular form in cross-section, hinged to the rear edge of the elevator frame, a lever mounted on the frame of the machine, connections intermediate said lever and the grain boards for 120 adjusting the latter by the former, and means for adjustably fixing the lever.
8. The combination with the platform and the elevator of a grain harvester, of a grain board hinged to the rear edge of the 125 130

platform, a grain board, of angular form in cross-section, hinged to the rear edge of the elevator frame, and means for detachably securing the said grain boards in their raised positions.

9. The combination with the platform and the elevator of a grain harvester, of a grain board hinged to the rear edge of the platform, a grain board, of angular form in cross-section, hinged to the rear edge of the elevator frame and having a flared extension at the lower end of its outer wall, and means for detachably securing the said grain boards in their raised positions.

10. The combination with the frame, the platform and the elevator of a grain harvester, of a grain board hinged to the rear edge of the platform, a grain board, of angular form in cross-section, hinged to the rear edge of the elevator frame and having a flared extension at the lower end of its outer wall, a lever mounted on the frame of the machine, connections intermediate said lever and the grain boards for adjusting the latter by the former, and means for adjustably fixing the lever.

11. The combination with the platform and the elevator of a grain harvester, said elevator comprising a frame, a lower apron, and an upper apron of a less width than the lower apron to afford an open space at the rear of the elevator; of a grain board hinged to the rear edge of the platform, a grain board of angular form in cross-section hinged to the rear edge of the elevator frame, and means for detachably securing the grain boards in their raised positions.

12. The combination with the platform and the elevator of a grain harvester, said elevator comprising a frame, a lower apron, and an upper apron of a less width than the lower apron to afford an open space at the rear of the elevator; of a grain board hinged to the rear edge of the platform, a grain board of angular form in cross-section hinged to the

rear edge of the elevator frame and having a flared extension at the lower end of its outer wall, and means for detachably securing the grain boards in their raised positions.

13. The combination with the platform and the elevator and the frame of a grain harvester, of a grain board hinged to the rear edge of the platform, a grain board hinged to the rear edge of the elevator frame, a lever mounted on the frame of the machine, means for adjustably fixing said lever, and connections intermediate the lever and the grain boards for working the latter by the former.

14. The combination with the platform, the frame and the elevator of a grain harvester, said elevator comprising a frame, a lower apron, and an upper apron of a less width than the lower apron to afford an open space at the rear of the elevator; of a grain board hinged to the rear edge of the platform and having a slotted bracket on its rear side, a grain board of angular form in cross-section hinged to the rear edge of the elevator frame and having a flared extension at the lower end of its outer wall, a hand lever fulcrumed at an intermediate point of its length on the frame of the machine, coöperating means on said frame and the lever for adjustably fixing the latter, a rock-shaft journaled in a bearing on the frame and having arms one of which is provided with an angular portion disposed and movable in the slotted bracket on the board at the rear of the platform, a link connecting the other arm of the rock-shaft and one arm of the hand lever, and a connection intermediate the other arm of the hand lever and the angular grain board.

In testimony whereof I have hereunto set my hand in presence of two subscribing witnesses.

WILLIAM J. AUMEN.
